UNITED STATES PATENT OFFICE.

GEORGE H. CHANDLEE, OF WASHINGTON, DISTRICT OF COLUMBIA.

PISTON-RING.

1,360,498.

Specification of Letters Patent. Patented Nov. 30, 1920.

Continuation of application Serial No. 766,801, filed May 10, 1913. This application filed July 16, 1915. Serial No. 40,318.

To all whom it may concern:

Be it known that I, GEORGE H. CHANDLEE, a citizen of the United States, residing at Washington, District of Columbia, have invented certain new and useful Improvements in Piston-Rings; and I do hereby declare the following to be a full, clear, and exact description of the invention, such as will enable others skilled in the art to which it appertains to make and use the same.

This invention relates to gas engines and has particular application to the means and method for reducing carbonization in the cylinders of the same, this application being a continuation of my co-pending application for Letters Patent filed May 10, 1913, Serial No. 766,801.

It is well recognized that one of the principal factors subversive of the efficiency of an explosive engine is the carbonization of lubricating oil within the cylinder. Consequently it is the practice to use a relatively light grade of cylinder oil, but even this, when supplied in excessive quantities, as is frequently unavoidable, results in the gradual accumulation of a hard deposit in the engine cylinder and on the exhaust valve. This deposit not only collects about and interferes with the action of the valve and the igniter, but under the high temperature of the exploding charges is exceedingly liable to be raised to the point of incandescence with the result that premature ignition of the charge takes place, driving the piston back in the cylinder and causing disagreeable and destructive shocks in addition to impairing and decreasing the efficiency of the engine.

Furthermore in the operation of modern high speed gas engines, the friction engendered between the rapidly moving piston equipped with the ordinary packing rings and the cylinder is so great that to prevent wearing and scoring it is necessary to supply oil in such quantities that a considerable portion of the resultant carbon, instead of being carried from the cylinder with the exploded charge settles therein and accumulates around the exhaust valve, on the end of the pistons and the igniter, consequently greatly decreasing the efficiency of the engine.

Another point to be taken into consideration with present day gas engines is that the peripheral cross diameter of the pistons

must be relatively wide, for if a narrow piston be employed the gaseous charge is liable to leak past the same from one side of the piston to the other. Consequently such a wide piston naturally provides a relatively large frictional contact surface which absorbs a large percentage of the energy of the engine.

I have found by experience that such detriments as carbonization and frictional wear on the engine may be remedied and eliminated to a marked degree by the use of piston packing rings embodied in my invention, and at the same time the cylinder will be efficiently lubricated with a minimum consumption of oil, thus not only avoiding the objections incident to the excessive use thereof, as above set forth, but also attaining a considerable saving in the amount and consequently the cost of the lubricant.

In the practice of my invention, I equip the ordinary gas engine with a suitable number of packing rings, each of which is formed with a series of novel peripheral grooves which are designed to receive the lubricant until the level of the lubricant in each groove lies at the outer edge of the webs or solid parts of the ring forming the walls of the groove. As a result of this construction, while the total width of such ring may be the same as that commonly employed in the art, the frictional bearing surface constituting the solid parts of the ring will be half, or less than half of such ordinary ring. This will be seen from the fact that my piston ring may be considered made of alternate circular webs and separated rings of lubricant, the latter during the reciprocation of the piston being confined in major part in the groove by the circumscribing walls of the cylinder. Thus the lubricant in the groove acts also as a seal to prevent the escape of gases from one side of the piston to the other, and I attain the same advantages in this respect as are inherent in the ordinary wide piston ring without the disadvantages of frictional wear on the cylinder walls. Furthermore, I propose to so construct the webs forming the grooves in the ring, that the outer or peripheral edges of the webs are relatively thin so that they may be readily worn to compensate for, and accommodate the form of ring to any irregularities in the inner wall of the cylinder.

With the above recited objects and others

of a similar nature in view, my invention consists in the construction, combination and arrangement of parts set forth in and falling within the scope of the appended 5 claims.

In the accompanying drawings:

Figure 1 is a longitudinal sectional view taken through a cylinder of a gas engine equipped with my invention, the piston being shown in elevation.

Fig. 2 is a similar view taken through a portion of an engine cylinder and showing the piston in elevation and as equipped with two forms of packing rings embraced in my 15 invention.

Fig. 3 is a detail sectional view of a portion of one form of piston ring embodying my invention.

Fig. 4 is a detail elevation of the piston 20 ring.

Referring now to the accompanying drawings in detail, the letter A designates an ordinary form of engine cylinder provided with the usual water jacket B. Within the 25 cylinder reciprocates the piston C, which in the present instance is shown as provided adjacent the ends with circumferential grooves 1, constructed in accordance with my invention.

The ring as illustrated comprises an annular body 2 which may be of cast iron or other suitable material and is provided at its outer periphery with a series of circumferential webs 3. These webs 3 are made by 35 forming the annular casting with a series of spaced grooves 4, each groove being separated from the neighboring grooves by one of the webs. Upon reference to Fig. 3 of the drawings, it will be seen that the webs 40 are approximately V-shaped in cross section with the peripheral edge 4 of each web forming a bearing surface which contacts with the inner wall of the cylinder during the reciprocation of the piston. The grooves 45 3 of course narrow as they recede into the body of the annular casting, the bottoms or apices of the grooves being formed by the bases of the webs.

Upon reference to Fig. 4 of the drawings, 50 it will be noted that the ring is "milled" to form a stepped lap, thus permitting the ring to be compressed when forced into the cylinder with the piston, so that by its resiliency, it will fit snugly against the inner wall of 55 the cylinder with the desired result.

When a ring is positioned in its groove 1 in the piston, as shown in Fig. 1, it will be seen that the circumferential grooves forming pockets for the reception of the lubricating oil which will be confined to some extent by the surrounding cylinder wall so 60 that the ring to all intents and purposes is made up of tapered circumferential webs alternating with oppositely tapered rings 65 of lubricating oil 6. As the piston recipro-

cates any wear on the ring takes place at the outer pointed circumferential edges 5 of the webs, so that the latter will wear as indicated by the dotted line in Fig. 3, and thereby compensate for any irregularity in 70 the cylinder wall. At the same time the webs and the rings of lubricant contained therebetween, prevent the escape of gas from one side of the piston to the other.

Now it is evident that my ring has approximately one-half or less than half of the frictional contact surface of the ordinary piston ring, although it is of the same body-width as the ordinary ring. This reduced frictional contact surface is due to the tapered form of the spaced webs, the reduced outer edges of which are the only parts of the ring which contact with the cylinder wall.

Therefore the same amount of lubricant is 85 not needed as is required for a modern high speed engine having the piston rings made with continuous or unbroken peripheral cylinder contacting surfaces, and consequently after each explosion in an engine 90 equipped with my invention, the amount of carbon generated is relatively small. Thus, instead of settling in the cylinder the carbon will be carried through the exhaust with the exploded charge. In other words, in 95 reducing by fully one-half the amount of cylinder oil required for proper lubrication, I correspondingly reduce the resultant carbon so that after each explosion, the cylinder does not contain a quantity of carbon which 100 is so excessive that it cannot be carried out with the exploded charge.

It will be noted that by the employment of a method and means herein described, the frictional contact surface of the piston is 105 greatly reduced and at the same time excessive carbonization is avoided, the result being that the efficiency of the engine is increased and the life of the working parts of such engine prolonged.

In the illustrated embodiment of the invention the marginal ribs constituting the line-contact edges are provided with convergent faces one of which is disposed at a right angle to the axis of the ring and constitutes an end face thereof.

It will be noted that in whichever position the ring is placed on the piston, the lower end face of the ring is at right angles to the ring axis and to the cylinder wall, while the 115 adjacent wall of the lowermost circumscribing groove, is at an acute angle to the ring axis and to the cylinder wall and is in outward convergent relation to the said end wall. The result is that in the down stroke, 120 the lower end face scrapes the oil from the cylinder wall, permitting only a small quantity to pass into the groove. This is because the end face is at right angles to the cylinder surface from which it is scraping oil. 125 130

On the up stroke, the lower wall of the circumscribing groove, drags over the cylinder wall at an acute angle to it. This acute angular relation of the lower groove wall to the cylinder wall, of course, permits the oil to pass out of the groove and beyond the said lower end face, more readily than it could pass by the said end face and into the groove. Furthermore, it will be noted that the successive lines of contact between the lower groove and the upper end face of the ring, serve to retard the flow of oil from the lower groove past the upper end face of the ring, to a greater degree than is the flow of oil retarded from the lower groove past the lower end face. In other words, more of the oil that is intercepted by the ring is turned back toward the crank case, than is permitted to find its way ultimately above the ring, all in performance of a fundamental objective of the present invention, which is to prevent carbonization.

What I claim is:

1. A resilient packing ring for effecting a quick wearing fit to a cylinder wall, having circumscribing grooves in its cylinder contacting periphery, with mutually adjacent walls of adjacent grooves converging toward and meeting at said periphery, with resultant ribs whose vertexes constitute substantially the entire initial cylinder contacting portion of the ring.

2. A resilient packing ring for effecting a quick wearing fit to a cylinder wall, having a continuous succession of circumscribing grooves in its cylinder-contacting periphery, with mutually adjacent walls of adjacent grooves converging toward and meeting at said periphery, with resultant ribs whose vertexes constitute substantially the entire initial cylinder contacting portion of the ring.

3. A resilient packing ring for effecting a quick wearing fit to a cylinder wall having its cylinder-contacting face circumferentially grooved with a plurality of resultant circumscribing ribs, the side walls of each of which ribs meet at the said periphery and afford a contacting line which lines constitute substantially the entire initial cylinder-contacting portion of the ring.

4. The method of effecting a fit between a cylinder and the longitudinally extensive portions of a contacting periphery of a resilient piston ring therein, which consists in circumferentially grooving the outer periphery of the ring with resultant spaced circumscribing ribs having convergent walls and resultant peripheral cylinder-contacting lines, that constitute substantially the entire initial contacting portion of the ring, placing the ring within the cylinder and then reciprocating the ring with its outer periphery in contact with the inner periphery of the cylinder until the lines of contact are worn

down and resultant longitudinally extensive spaced contacting surfaces for the ring ensue.

5. A resilient packing ring having its cylinder-contacting face circumferentially grooved, with a plurality of resultant endless ribs, the side walls of each of which ribs meet at the periphery and afford a cylinder contacting line which lines constitute substantially the entire initial cylinder contacting portion of the ring, the outer walls of the ribs being at right angles to the axis of the ring to effect an efficient scraping of the wall of the cylinder in both directions of the movement of the ring therein.

6. A resilient piston packing ring having faces converging to one or more peripheral line contacting edges constituting substantially the entire initial cylinder contacting portion of the ring.

7. A resilient piston packing ring having faces converging to one or more peripheral line contacting edges constituting substantially the entire initial cylinder contacting portion of the ring, one of said faces being at right angles to the axis of the ring.

8. A resilient piston packing ring having faces converging to one or more peripheral quick wearing contact edges constituting substantially the entire initial cylinder contacting portion of the ring, one of the said faces being at right angles to the axis of the ring and constituting an end face of the ring.

9. In an explosive engine, a piston, a resilient piston ring having its crank end face disposed at an angle to the ring axis and having a circumscribing, peripheral groove, the side wall of the groove next said crank end face substantially meeting said crank end face at its outer edge in outwardly convergent relation thereto, said wall of the groove being at an angle to the ring axis that is less than the angle of said crank face to the ring axis.

10. In an explosive engine, a piston, a resilient piston ring having its crank end face disposed at right angles to the ring axis and having a concentric groove, the wall of the groove next said crank end face substantially meeting said crank end face at its outer edge in outwardly convergent relation thereto.

11. The combination with an explosive engine piston, of a resilient packing ring thereon, the ring having a concentric groove at its crank end face, the wall of the groove at the crank side of the groove being in outwardly convergent relation to the crank end face of the ring, which crank end face of the ring is at a greater angle to the ring axis than is the said wall of the groove.

12. In an explosive engine, a piston, a piston packing ring having a circumscribing rib for impelling oil in one direction to a degree greater than in the opposite di-

rection, wherein the side walls of the rib are disposed at angles of different degrees to the axis of the ring.

13. An explosive engine resilient piston packing ring for effecting an initially quick and gradually retarded wearing contact with the cylinder wall, wherein the cylinder contacting face consists substantially of one or

more circumferential ribs, of which the side surfaces converge toward and substantially 10 meet at the periphery of the ring.

In testimony whereof, I affix my signature, in the presence of a witness.

GEORGE H. CHANDLEE.

Witness:

A. ELLISON.
